UNITED STATES PATENT OFFICE.

WILLIAM H. MCKINNEY, JR., OF MEMPHIS, TENNESSEE, ASSIGNOR TO COTTON BUCKLE & TAG CO., INC., A CORPORATION OF TENNESSEE.

TOILET APPLIANCE.

Application filed November 4, 1926. Serial No. 146,134.

This invention relates to toilet appliances and more specifically to a dual toilet seat.

It is an object of this invention to provide a supplementary toilet seat particularly designed for use by children, which may be readily attached to any type of toilet seat now in use.

Another object is to devise a seat of this character which may be attached or detached without altering the structure of the main seat.

A further object is to provide a supplementary seat which may be raised or lowered independently of the main seat.

With these and other objects in view which will appear from the following description, the invention comprises the provision of a supplementary or secondary seat which is supported by the usual seat but is pivotal independently of it.

To make the invention more clearly understood, I have illustrated a practical embodiment of it in the annexed drawings, throughout which similar reference numbers refer to like parts in the several views, of which

Figure 1 is a top plan view of the two seats;

Fig. 2 is an elevation showing the mounting and relative position of the seats;

Fig. 3 is a detail view of the attaching means of the auxiliary seat.

In the drawings there is shown a bowl 1 of any conventional type. This is provided with the usual rear extension or shoulder 2. Passing through the extension and firmly secured thereto by any suitable means are the supporting standards 3. Interposed between the shouldered standards and the bowl are rubber washers 4.

Each standard 3 is formed with an integral angularly disposed reduced stub shaft portion adapted to be inserted in the hollow pivot bolt 5. The usual seat 6 and cover 7 are mounted for swinging movement about the longitudinal axis of the pivot 5. The seat is pivotally secured to this member by means of the brackets 8. This bracket is formed with a flat U-shaped portion to which the cover is secured by means of screws 9. The arms of the bracket are extended downwardly and are apertured at their lower ends, thereby presenting collars to receive the pivot 5.

Affixed to the bottom of the seat 6 is a bracket member 10 having extending aper-

tured arms which receive the pivot 5. In this manner the seat and cover are pivotally secured to one transverse member. The described structure represents a standard form of toilet seat now in use.

I have devised a supplementary seat designed for the use of small children, which may be securely attached to the main seat without the use of screws, bolts or any other permanent fastening means. This comprises a seat 12, of any desired size and configuration. The seat is provided on the bottom with rubber pads 13 which rest on the main seat and serve to prevent actual contact of the two. Secured to the supplementary seat 12 is a U-shaped bracket having a flat apertured bearing surface 14 and collared projecting arms 15. I prefer to mortise the bottom of the seat 12 to receive therein the bearing portion 14 and the adjacent sections of the arms 15. With this construction the bottom of the seat is flush with the supporting bracket and the assembled seat may be positioned very close to the main or usual seat.

The collared ends of the arms 15 are mounted on the transverse pin 16. As shown in Fig. 2, the longitudinal axis of this pin is laterally and horizontally spaced from the pivot pin 5, and is adapted to rest on the rear portion of the seat 6. To prevent scarification of the main seat, I may provide a pair of rubber washers adapted to surround the pivot 16 near each end and thus prevent contact of the metal parts with the enameled seat.

To secure the pivot 16 to the seat 6 in a manner to preclude displacement and yet allow for ready detachability, I provide a pair of clamps 17. Each of the clamp members is formed with a reversely turned hooked portion 18 adapted to engage the flat bottom of the main seat. The opposite end of each clamp member is provided with an apertured bushing 19, into which projects the pivot 16. To maintain the collared portions or arms 17 and 15 in proper position on the pivot 16, the ends of the pivot may be headed or may be supplied with threaded ends. Intermediate its ends there is secured to the spindle 16 a collar 20. This collar is formed with a threaded tap with which registers the set screw 21. The function of this set screw, as will be appreciated, is to determine the position of the collar relative to the spindle 16. As shown particularly in

Fig. 3, the collar is extended to present an aperture 22. Passing through this aperture and secured thereto is one end of a spiral spring 23. To the other end of the spring there is attached a small hook 24 which bears against the bottom of the seat with a force determined by the tension of the spring 22.

The mode of assembly of the toilet appliance will be apparent from the foregoing description. The hooked ends 18 of the arm 17 are placed beneath the seat so that the spindle 16 extends transversely across the seat parallel to the pivot 5. The hook 24 is then engaged with the bowed portion of the main seat. The spindle 16 and associated parts are then held to the seat by the force exerted by the tension spring 23. This prevents vertical movement of the spindle and connected co-operating parts with respect to the seat 6. It will be perceived from an inspection of Fig. 1, that the arms 17 are positioned closely adjacent the knobs of the standards 3. This mounting prevents lateral movement of the supplementary seat with respect to the main seat.

As alluded to hereinbefore, the axis of the spindle 16 is in a plane below that of the pivot 5. By reason of this arrangement the cover 7 may be lowered to rest flatly on the supplementary seat without exerting any strain on the pivot 5 and standards 3. The spindle 16 is also laterally spaced from the pivot 5. This arrangement presents the advantage of allowing the supplementary seat to be raised to inoperative position when the seat cover is in any position to the left of a vertical plane, as viewed in Fig. 2. This eliminates a disadvantage inhering in some prior devices of this general character, in which the supplementary seat was mounted on the same pivot as that which supported the main seat and cover. In such constructions it was necessary to move the cover some distance to the rear of a vertical plane in order that the supplementary seat might attain a position of rest. This feature is of considerable importance at the present time. The demands for economy of space in modern apartments require that the toilet bowl be placed as near the wall and flush basin as possible.

It will be seen that I have provided a supplementary seat structure that may be easily and firmly attached to any standard seat. The seat may be easily removed for cleansing and hence this structure is easily kept in a sanitary condition. The relative position of the arm 17 with respect to the standards 3 and the provision of the spring and rubber buffers prevent injury to the main seat. All of these advantages are obtained by a structure which comprehends but few and easily replaceable parts.

Although the disclosures herein given ex-

emplify what is now considered to be a preferable embodiment of the invention, it is to be understood that it is not my intention to be necessarily limited thereto in an interpretation of the claims, as modifications and adaptations within the limits of the claims can be made without departing from the nature or scope of the invention.

I claim:

1. A toilet seating appliance comprising a standard, a pivot carried by the standard, a main seat and cover therefor mounted on the pivot, a supplementary seat carried by the main seat and pivotally mounted thereon independently of the pivot. 75

2. A toilet seating appliance comprising a standard fixed to the bowl, a pivot carried by the standard, a main seat and cover rotatably mounted on the pivot, a supplementary seat carried by the main seat and pivoted thereon, the pivots of the main and supplementary seats being horizontally and laterally spaced. 80

3. A toilet seating appliance comprising a pivoted main seat, a clamp attached to the main seat including a pivot member attached to the seat and a supplementary seat rotatable about the pivot member. 90

4. A toilet seating appliance comprising a pivoted main seat, a detachable clamp including a pivot member attached to the seat, and a supplementary seat pivotal about the pivot member. 95

5. A toilet seating appliance comprising a pivoted main seat, a clamp structure including a pivot mounted on the main seat, a supplementary seat pivotal about the pivot member, the pivotal axis of the supplementary seat being in a plane lower than the pivotal axis of the main seat. 100

6. A toilet seating appliance comprising spaced standards fixed to a bowl, a pivot mounted in the standards, a main seat and cover coacting with the pivot, a supplementary seat pivotal about an axis forwardly and laterally spaced from the pivotal axis of the main seat and cover. 110

7. A toilet seating appliance comprising a pivoted main seat, a clamp including a pair of members engaging the rear edge of the main seat, a transverse bolt connecting the seat engaging members and a spring tensioned means attached to the bolt intermediate the members and engaging a portion of the main seat. 115

8. A toilet seating appliance comprising a supplementary seat, a pair of spaced arms connected with the seat, a pivot member on which the arms are rotatably mounted, a plurality of clamping members carried by the pivot member and adapted to detachably secure the supplementary seat to the main seat. 125

9. A toilet appliance comprising a main seat having a relatively large opening and a 130

second seat having a relatively small opening adapted to overlie the first seat and means including a plurality of seat engaging members and a spring tensioned hook to detachably secure the second seat to the main seat.

10. A toilet seating appliance comprising a pivoted main seat, a supplementary seat clamping means engaging a plurality of faces on the main seat and a pivot carried by the clamping means to rotatably mount the supplementary seat.

11. A toilet seating appliance comprising a main seat, a supplementary seat adapted to overlie the main seat, means to pivotally mount the supplementary seat on the main seat including an extensible clamp.

12. A toilet seating appliance comprising a main seat, a supplementary seat, means to secure the supplementary seat to the main

seat for pivotal movement thereon including a clamp member engaging the main seat and provided with a pivot, a second clamp member engaging the seat and adjustable with respect to the first clamp member.

13. A toilet seating appliance comprising a main seat, a supplementary seat adapted to overlie the main seat, means to secure the supplementary seat to the main seat including an adjustable clamp and a pivot operationally associated with the clamp.

14. A toilet seating appliance comprising spaced standards, a main seat pivotally mounted on the standards, a supplementary seat provided with an adjustable clamp connected to the pivot.

In testimony whereof I affix my signature.

WILLIAM H. McKINNEY, JR.
